UNITED STATES PATENT OFFICE.

ALBERT C. JOHNSON, OF WILMINGTON, DELAWARE.

ORE-ROASTING FURNACE.

SPECIFICATION forming part of Letters Patent No. 391,151, dated October 16, 1888.

Application filed June 17, 1887. Serial No. 241,627. (No model.)

To all whom it may concern:

Be it known that I, ALBERT C. JOHNSON, of 5
Wilmington, in the county of New Castle and
State of Delaware, have invented a new and
Improved Ore-Roasting Furnace, of which the
following is a full, clear, and exact description.

The object of my invention is to provide a
new and improved ore-roasting furnace, which
is simple and durable in construction and very
10 effective in operation, for desulphurizing copper
ores, iron pyrites, gold-bearing sulphur-
rets, and other ores.

The invention consists in the construction
and arrangement of various parts and details
15 and combinations of the same, as will be fully
described hereinafter, and then pointed out in
the claims.

Reference is to be had to the accompanying
drawings, forming a part of this specification,
20 in which similar letters of reference indicate
corresponding parts in all the figures.

Figure 1 is a side elevation of my improvement.
Figs. 2 and 3 are plan views of the partition
25 plates or shelves. Fig. 4 is an enlarged
plan view of the hopper. Fig. 5 is a plan view
of the central part of the top plate. Fig. 6 is
a plan view of the hopper-disk. Figs. 7 and
30 8 are enlarged inverted plan views of the raking-bars.
Fig. 9 shows views of the teeth of the
spacing-blocks for the teeth of the raking-bars.

My improved ore-roasting furnace is provided
with a cylindrical shell, A, of brick or
other suitable material, in which are formed
35 the compartments B, C, D, E, and F, placed
one above the other, and of which the upper-
most compartment, B, is covered by a top
plate, G, and the compartments B and C are
separated from each other by a partition-plate,
40 H, provided near its periphery with the seg-
mental slots H', as shown in Fig. 2.

The compartments C and D are separated by
the partition-plate I, provided with a central
aperture, I', and the compartments D and E
45 are separated by another partition-plate, I.
The bottom of the compartment F is formed by a plate, J,
provided near its periphery on one side with
an opening, J', leading into the spout or chute
50 J'', supported in the cylindrical casing A and
extending downward and to the outside of the

said casing. Two spouts or chutes, J'', placed
opposite each other, may be employed, if de-
sired.

In the center of the cylindrical casing A, and
passing through the several plates G, H, I, and
J, is held the vertical shaft K, supported at
its lower end by a step, K', and also held in
suitable bearings formed in the center of the 60
plates J, H, and G. On the end of the shaft
K, above the top plate, G, is secured the sleeve
L', supporting at its lower end the disk L, pro-
vided with openings L'', placed diametrically
opposite each other. The disk L revolves on 65
top of the plate G, and is held in a hopper, N,
provided above said disk L, with a cross-plate,
N', having the openings N'', corresponding in
size and shape to the openings L'' of the disk L,
and placed diametrically opposite each other. 70

Directly under each opening N'' is held a
slide, N'', which extends to the outside of the
hopper N, and serves to increase or diminish
the opening N'', so as to feed more or less ore
to the furnace. In the top plate, G, and di- 75
rectly below the disk L, are formed the open-
ings G', placed diametrically opposite each
other and corresponding with the openings in
the plate N', and the revolving disk L. Said
openings G' are placed at right angles to the 80
openings N'' in the hopper N, so that when the
openings L'' of the revolving disk L register
with the openings N'' of the hopper they do
not register with the openings G' of the top
plate, G, and vice versa.

In each of the compartments B, C, D, E,
and F are placed the raking-bars O, each con-
sisting of the slotted arms P, clamped to the
shaft K by suitable means and extending in a
straight line equal distances on each side of 90
said shaft K. On the slotted arms P are held
the raking fingers or teeth Q, and between each
two successive fingers are placed the spacing-
blocks R, which may be of different widths for
regulating the distances between the several 95
teeth or fingers Q. The spacing-blocks R and
the fingers Q are held in place in the slotted
arms P by a set-screw, S, screwing in an end
plate, P', secured to the outer ends of the slotted
arms P, said set-screw S screwing against the 100
outermost finger held in the arms P. A tooth,
Q, or spacing-block R may be easily removed
from the arms P, in case one is broken, by re-
moving the end plate, P', whereby the several

spacing blocks and fingers held between said arms can be easily removed and replaced by new ones.

Each of the fingers Q is provided on its bottom with an inclined plate, Q', extending to near the tops of the partition-plates, and arranged in such a manner in the several compartments, B, C, D, E, and F, that the raking-bars O in the compartment B move the ore outward toward the openings H', while in the compartment C the incline Q' is so arranged as to move the ores inward toward the center into the opening I', and in the next following compartment D the inclines Q' are placed to move the ore outward again to the openings H', and in the next following compartment E the teeth Q are arranged to move the ore inward again toward the center of the plate I and into the opening I', and in the lowest compartment, F, the teeth Q move the ore outward toward and into the opening J', so that the ore falls into the chute J² and is delivered to the outside of the furnace.

The shaft K is provided at its lower end with a bevel gear-wheel, T, into which meshes the pinion T', secured to the driving-shaft T², which, when rotated by suitable means, imparts a rotary motion to the shaft K in the direction of the arrow a'. (Shown in Figs. 7 and

8.) Instead of the gear-wheels T and T', I may employ other means for revolving said shaft K. Into each compartment B, C, D, E, and F lead a number of doors for starting a fire in the respective compartments and for other purposes.

35 The operation is as follows: The ore placed in the hopper N passes through the openings N' into the openings L' of the disk L, which revolves with the shaft K and transmits the ore to the openings G' in the top plate, G, 40 whereby the ore falls through said openings G' into the center of the compartment B, and is moved outward on the top of the partition-plate H by the raking-bars O until the ore is pushed through the openings H' into the compartment C, in which the raking-bars O move the ore inward and discharge the same through the opening I' into the next following compartment B, and in the latter the ore is transmitted from the top of the partition-plate H 45 outward and through the opening H' into the

compartment E, from which the ore is moved inward by the raking-bars O through the opening I' into the lowest compartment, F, and in the latter the ore is again moved outward and discharged through the spout or 55 spouts J², above described.

It will be seen that the ore is regularly fed into the top compartment, B, by the revolving of the disk L, as the openings of the latter connect alternately with the openings in the 60 hopper and with the openings G' in the top plate, G. The ore is gradually moved from one compartment to the other, and is agitated in each compartment by the raking teeth or fingers, which at the same time impart an outward or inward motion to said ore.

65 My improved furnace does not require a supply of external heat, as, on starting, the furnace is heated to the required temperature by burning wood or other suitable fuel in the 70 several compartments, B, C, D, E, and F, after which the temperature in the several compartments is sustained and held permanently by the combustion of material under treatment—that is, the sulphur or other substance contained in the ore.

75 Having thus described my invention, what I claim as new, and desire to secure by Letters Patent, is—

1. In an ore-roasting furnace, a rake comprising a longitudinally-slotted arm, separate and independent teeth or fingers held in said slot, and a plate closing the outer or open end of the slot, and provided with a screw entering the slot and bearing against the outer finger or tooth, substantially as set forth. 80

2. In an ore-roasting furnace, a rake consisting in the slotted arm P, the separate and independent T-headed teeth or fingers held in said slot and formed on their lower faces 85 with the inclined plates Q', the T-headed spacing-blocks R, also held in said slot, and the plate P', closing the outer or open end of the slot, substantially as set forth, whereby any tooth may be removed and the distance between the teeth be properly spaced. 90

ALBERT C. JOHNSON.
